FIRE FIGHTING AND RESCUE APPARATUS

Henry Frank Buchheit, Milwaukee, Wis., assignor of one-half to Annie Mater

Application February 4, 1937, Serial No. 124,151

2 Claims. (Cl. 227—22)

This invention relates to improvements in a character of apparatus particularly advantageous for usage in fire fighting and rescue work, having for an object, to provide a device of the character indicated, equipped with means for receiving and safely guarding therein either firemen or other persons during fire fighting or rescue work, the person-receiving means being carried by mechanism so operable that it may be raised or lowered to any desired height or point, and when desired, or required, may be returned to its initial starting and lowered position, or to any desired intermediate point.

It is also an object of the invention to provide the apparatus with a novel form of means whereby the compartment raising and lowering mechanism may be, at the will of an operator of the apparatus, selectively inclined or tilted so as to permit the directing of the compartment to a desired objective, notwithstanding the fact that such objective may be located at a point above and lateral of the apparatus.

A further objective of the invention may be stated to reside in providing the compartment or person-receiving means of the apparatus with a novel form of traction or creeping means, this latter means being adapted, with inclining or tilting of the apparatus elevating mechanism, to engage with a wall or similar surface being traversed by the compartment, and causing such compartment to be effectually braced during its upward or downward movement, consequently, insuring greater safety to the occupants thereof, as well as the successful operation of the apparatus.

Yet another object of the invention is to provide the apparatus compartment with means which are operable in conjunction with the traction or creeping means in a manner to cause the compartment to be automatically levelled during such time as it is being raised or lowered to or from an objective, such automatic levelling means being operated from the said traction or creeping means in a manner whereby when the traction means are moving over a wall or other surface which is other than vertical, the movement of the traction means will be transmitted to the compartment in such a manner that the floor thereof will be maintained substantially level and will remain in such position during movement of the apparatus compartment.

A still further object of the invention may be stated to reside in providing the elevating mechanism of the apparatus with an adjustable and extensible water conduit or hose, hence, permit-

ting the flowing of water from a suitable source of supply therethrough, and by consequence, a conduction of the water upwardly with respect to the apparatus to such a point where it may be advantageously discharged or directed therefrom for fire fighting or extinguishing purposes.

Other objects of the invention will be in part obvious and in part pointed out hereinafter.

In order that the invention and its mode of operation may be readily understood by those skilled in the art to which it appertains, I have in the accompanying illustrative drawings and in the following detailed description based thereupon, set out one possible embodiment of my invention.

In these drawings:

Figure 1 is a side elevation of the improved apparatus, showing the same mounted upon a mobile carrier, the latter being fragmentarily illustrated;

Figure 2 is a vertical transverse section taken on the line 2—2 of Figure 1, looking in the direction in which the arrows point;

Figure 3 is an enlarged section taken transversely through the Figure 1, along the line 3—3 thereof, looking in the direction in which the arrows point;

Figure 4 is a top plan view of the apparatus;

Figure 5 is an enlarged fragmentary detail in horizontal section taken on the line 5—5 of Figure 3, looking in the direction in which the arrows point;

Figure 6 is a side elevation of the apparatus in one of its distended positions; and,

Figure 7 is a similar view taken at substantially right angles to the Figure 6.

Having more particular reference to the drawings, in connection with which like characters of reference will designate corresponding parts throughout, the invention may be stated, generally, to comprehend a suitable mobile carrier, designated by the numeral 1, such for example, as a motor-driven truck or the like, a bed 2, so constructed as to permit of tilting or inclining of the elevating apparatus, (hereinafter described), either longitudinally or transversely of the same, as will be hereinafter more fully described, an elevating mechanism, designated in its entirety by the numeral 3, and a car or compartment, referred to in its entirety by the numeral 4.

The mobile carrier 1 is equipped with a body or chassis of a size sufficient to permit of the mounting of the bed 2 thereon. Said bed is of substantially rectangular configuration, having standards 5 fixedly connected to the opposite ends

of the main sills or supporting bars, the standards, in turn, being fixedly anchored to appropriate and adjacent portions of the carrier 1. A transversely disposed rocker shaft 6 is mounted 5 in suitable bearings adjacent one end of the bed 2, while portions of the main sills or supporting bars 7 of the bed are formed with complementally and relatively opposed annular frames 8; struts or bracing rods, generally designated by 10 the numeral 9, being disposed transversely of the bed and having fixed connection at their opposite ends with adjacent portions of the annular frames 8, whereby to relatively brace the same.

Vertically disposed screw-threaded shafts 10 15 are rotatably mounted in bearings 11 provided upon the basal portions of each of the annular frames 8, the upper portions of the shafts being rotatably received through bearings 12 supported upon the upper portions of each of said frames 20 at points diametrically opposite the bearings 11. A substantially U-shaped bar 13 is fixedly connected to the upper sides of the bearings 12 and to the adjacent portions of the annular frames 8 and serves as a means for rotatably supporting 25 from its lateral extremities, a shaft 14 extending transversely of the bed 2 and longitudinally of the bar 13. Meshing bevel gears, generally identified by the numeral 15, are mounted upon the upper ends of the vertical screw-threaded shafts 30 10 and adjacent portions of the shaft 14, so that with rotation of the latter, as by the connection of a motor or like source of power, not shown, to the extended end 14' thereof, collective rotary movement will be imparted to the screw-threaded 35 shafts 10.

Relatively spaced supporting arms 16, having certain of their ends slotted as at 17, are pivotally mounted upon the hereinbefore described transverse rocker shaft 6, the shaft being received in said slots 17 of the arms 16, as is shown in the Figure 1. The remaining or inner ends of these arms 16 are pivotally connected, as at 18, to collars 19, each of which have screw-threaded engagement with their respective screw-threaded shafts 10. Thus, it will be understood that with collective rotation of the screw-threaded shafts 10, pivotal movement of the supporting arms 16 will be effected, the direction of which will be dependent upon the direction of 50 collective rotation of the screw-threaded shafts 10.

The elevating mechanism, hereinbefore generally identified by the numeral 3, is supported upon the bed 2, and more particularly, upon the 55 pivotally mounted arms 16 thereof. This mechanism is received upon a secondary supporting bed, consisting of obliquely disposed bars 20, fixedly interconnected at their upper ends and supporting bearings 21, adjacent the same, the 60 lower end of the bars being fixedly mounted upon adjacent portions of the supporting arms 16, beyond the annular frames 8 of the bed 2. A pair of the obliquely disposed bars 20 are arranged in relatively longitudinal relation upon the arms 16. 65 Other supports of substantially reversed L-shaped formation, designated by the numeral 22 are provided the secondary bed adjacent the bars 20 of one side of said secondary bed, the horizontal extensions 22' thereof being fixedly connected, as at 23, to adjacent portions of such arms 20; the remaining ends of the supports 22, together with the adjacent portions of the arms 20 being fixedly connected to their respective 70 portions of the adjacent arms 16, as at 24. Rotatably mounted in the longitudinally spaced

bearings 21 is a shaft 25, about which there is immovably received a tubular element 26, the purpose of which will be hereinafter described. The outer end of the shaft 25 is extended and has a pair of juxtaposed sprocket wheels 27 5 fixedly mounted thereon, the extremity of the shaft being adapted to be connected, as through suitable gearing (not shown) with a motor or other source of power (also not shown). The secondary bed thus described, provides an effectual supporting means for the elevating mechanism. Said mechanism comprehends a pair of relatively spaced supporting bars 28 disposed transversely over the non-rotatable tubular element 26 carried about the shaft 25, the former 10 being securely connected to the bars 28 by means of U-shaped fasteners 29 engaged thereabout and having their extremities effectually anchored in adjacent portions of said bars 28, as is shown in the Figure 3. In this way, a pivotal support 15 is provided the transversely disposed bars 28.

Disposed transversely with respect to the bars 28 and fixedly mounted upon the opposite extremities of each, are a pair of track members 30, each of which rotatably supports therein a longitudinally disposed screw-threaded shaft 31. Certain of the ends of each of said shafts 31 are extended beyond their respective track members 30 and have sprocket wheels 32 fixedly carried thereupon. Sprocket chains 33 and 34 are provided the sprocket wheels 32, the opposite ends of which are engaged with the sprocket wheels 27, mounted upon the extended end of the shaft 25. Consequently, it will be seen that with rotation of the shaft 25, collective rotation will be 35 imparted to the screw-threaded shafts 31.

The above referred to shafts 31, it should be noted, have their opposite portions oppositely screw-threaded, as is indicated by the numeral 31' in the Figure 1. Engaged with these oppositely screw-threaded portions 31' of each of the shafts 31, are correspondingly screw-threaded collars 35, the same being slidably and snugly received within their respective track members 30, as is shown in the Figure 3. With collective rotation of the shafts 31, it will be thus seen that the collars 35 will be caused to move longitudinally through their respective track members 30 in opposite directions. Each of the collars 35 is provided with upstanding tongues 36 having openings formed therethrough and receiving thereover, the adjacent bifurcated ends of levers, generally indicated by the numeral 37, whereupon connecting rods 38 are passed through the bifurcated portions of said levers and the openings of the adjacent tongues 36; the opposite ends of said connecting rods being preferably screw-threaded and each thereof being engaged with suitable locking nuts 39, for an obvious purpose. Those portions of each of the connecting rods 38 intermediate of the paired collars 35 are received through tubular spacing members 40, whereby to insure fixed relative positioning as 55 between the paired collars 35, and hence, insure free sliding movement of the same in their respective track members 30.

The levers 37 are crossed, intermediate of their ends and are pivotally interconnected by means of a transversely disposed connecting rod 38' 70 passing therethrough; the intermediate portion of said connecting rod 38' having the tubular spacing member 40' engaged thereover, and the opposite ends of the connecting rod being suitably locked against displacement with respect to 75

the crossed and pivotally interconnected levers 37.

A plurality of relatively crossed and pivotally interconnected levers are arranged above the levers 37 and the adjacent ends of certain of said levers 37 are connected thereto, thus presenting what is generally known in the art as a lazy-tong construction. The upper or free ends of the levers constituting the lazy-tong construction are slidably engaged in the slotted side plates 41 of the bed (presently described) for the car or compartment 4.

The car or compartment bed consists of a substantially rectangularly shaped frame 42 having upright angle irons 43 fixedly mounted adjacent the various corners thereof, while upon the intermediate portions of the opposite ends of said frame, supporting brackets 44 are firmly mounted. Pivotally supported between the brackets 44 is the compartment 4 consisting of a cage-like structure, one of the side walls of which is preferably provided with a doorway 45, adapted to be normally closed by means of a sliding door 46, the remainder of the walls and the top of the compartment being constructed of heavy reticulated material, such as indicated at 47 supported upon suitable forms, generally indicated by the numeral 48. The flooring 49 of the compartment is preferably constructed of sheet material and if desired, a form of slidable or extendible walk 50 may be mounted therein in proximity to the doorway 45, so that when communication is to be effected as between the compartment 4 and an adjacent point or objective, said walk 50 may be laterally distended, after the fashion as indicated in the Figure 7, thus, permitting of ingress or egress into or from said compartment 4.

At this point, it is to be noted that the compartment 4 is received between the angle irons 43 and therefore, that the same will be effectually guarded or shielded from destructive contact of the sides thereof with foreign objects.

Laterally disposed bearing brackets 51 are fixedly connected to the upright angle irons 43 upon one side of the compartment bed 42, rotatably supporting a bar 52 therein. The opposite ends of the bar 52 fixedly carry supporting arms 53, the opposite ends of which are bifurcated and rotatably support wheels 54 therebetween. These wheels 54 receive endless or belt-like treads 55 over and about their peripheral portions, thus providing the same with self-laying treads of the tractor type. The intermediate portion of the bar 52 has an arm 56 fixedly mounted thereupon, which arm, in turn, is pivotally connected to links 57 extended into pivotal engagement with a vertically disposed bearing plate 58 mounted for transverse slidable movement in a track member 59 mounted upon an intermediate portion of the compartment bed or frame 42, as is shown in the Figures 1 and 3. The upper side of this bearing plate 58, as will be noted upon reference to the Figure 3, is formed with oppositely inclined portions, which portions are adapted to have sliding bearing engagement with a substantially reversed V-shaped pocket 60 formed in the sheet flooring 49 of the compartment 4. It will be therefore seen that because of the pivotal mounting of the compartment 4 between the brackets 44, that with sliding movement of the plate 58 in its track 59, said compartment 4 will be tilted or pivoted with respect to its support. Hence, when the endless tread 55 of the pairs of wheels 54 engage with a wall or other surface, such as indicated at 61, the posi-

tioning of the wheels during such engagement will be correspondingly matched by the positioning of the compartment 4. Consequently, should the endless treads 55 of the wheels 54 move over a surface other than a vertical or a perpendicular one, it will be understood that this out-of-the-vertical positioning of said wheels 54 will transmit sliding movement to the plate 58, which in turn, in sliding through the pocket 60 of the compartment flooring will effect an automatic levelling of such flooring and thereby, permit the occupants of the compartment 4 to retain their feet.

With a view toward providing the occupants of the compartment 4 with means for manually controlling the positioning of the wheels 54 with relation to said compartment, the bar 52 may be and preferably is provided with a fixedly mounted sprocket wheel 62 about which a sprocket chain 63 is engaged, the remaining end of said sprocket chain engaging about a second sprocket wheel 64 mounted upon a stub-shaft journaled in suitable bearings in one end wall of the compartment 4; the inner end of said stub-shaft being provided with a crank handle 66, which is arranged within the compartment 4 and is accessible to the occupants thereof. Thus, by rotating the shaft 65 through its crank handle, rocking motion may be transmitted to the bar 52, hence, adjusting or moving the wheels 54 carried thereupon through the desired relative positioning with respect to the compartment 4. In this way, should it become necessary, level positioning of the flooring 49 of the compartment 4 may be effected by occupants of said compartment.

In order that transverse tilting or inclining of the elevating mechanism may be effected, a pair of cylinders having open upper ends, designated by the numeral 67, are fixedly mounted, in relatively vertical positions, upon a supporting bar 68 disposed between and fixedly connected to the upper portions of the supports 22. Heavy expandible coil springs 69 are received within each of the cylinders 67; said cylinders, in turn, longitudinally receiving therethrough plungers 70, connected to and depending from an adjacent portion of the elevating mechanism 3. Each of the plungers 70, it will be noted, are provided with stop devices 71 upon their lower ends and upon their intermediate portions, the stop devices 50 carried upon the intermediate portions being adapted to have bearing engagement with the adjacent ends of their respective expandible coil springs 69. By reason of this construction, the plungers 70 will be normally maintained in their uppermost positions, because of the engagement of their intermediate stop devices 71 with the expandible coiled springs 69 and consequently thereupon, the elevating mechanism 3 will be moved to and retained in a tilted or inclined position, because of its pivotal support upon the tubular element 26 carried by the shaft 25. To enable an operator of the apparatus to pivot or move the elevating mechanism 3 in a direction reverse to that attained by it under influence of the spring pressed plungers 70, I mount upon an intermediate portion of the said elevating mechanism 3, opposite the side equipped with the plungers 70, a plunger or arm 71'. About the upper end of this arm 71', an expandible coiled spring 72 is engaged, one end of which has fixed connection with the arm, as at 73 while the opposite end has fixed bearing engagement with an adjacent portion of its receiving and supporting bracket, as at 74. The lower end of this arm 71' 75

is provided with a head 75 to which the adjacent ends of the links of a toggle construction, designated by the numeral 76, are pivoted, as at 77. The free or remaining ends of the links of the toggle construction are pivotally connected to a bracket 78 fixed to an adjacent portion of one of the supporting arms 16; the intermediate ends of the links of the toggle construction having collars 79 and 80 connected thereto, the latter being internally screw-threaded. A shaft 81 is rotatably received through the collars 79 and 80, one portion thereof being screw-threaded as at 82 whereby to engage with the internal screw threads of the collar 80. The remaining collar 15 79 is prevented from having movement longitudinally of the shaft 81 by means of a stop pin 83 passed through an adjacent part of said shaft and having its opposite ends in engagement with the adjacent portion of said collar 79, as is shown 20 in the Figure 3. By rotating the shaft 81, either manually or otherwise, it will be seen that the screw-threaded collar 80 will be moved over the screw-threaded portion 82 of said shaft. Thus, with movement of the collar 80 over the shaft in 25 an inward direction with respect to the elevating mechanism, a downward pull will be imparted to the adjacent and connected side of said elevating mechanism and this pull, in conjunction with the thrust imparted to the opposite side thereof from 30 the spring actuated plungers 70 will cause said elevating mechanism to be selectively tilted or inclined to the desired degree transversely of and with respect to the bed 2. With rotation of the shaft 81 in a reverse direction, it will be seen 35 that the screw-threaded collar 80 will move over its screw-threaded portion 82 in the opposite direction and in so doing, the toggle construction will be expanded, hence, imparting an upward thrust to the adjacent and connected side of said 40 elevating mechanism, causing the latter to be tilted or inclined in an opposite direction and against the spring thrust action of the plungers 70 engaging with their respective expansible coiled springs 69 in the several cylinders 67.

45 If desired, certain of the levers of the toggle construction comprehended by the elevating mechanism 3 may be provided with sections of piping, such as generally designated by the numeral 84. The meeting or adjacent ends of 50 these pipe sections are interconnected by adjustable elbow fittings 85 and in this way, a water pipe line is provided the elevating mechanism, the lower end of said pipe being equipped with a suitable coupling or fitting to facilitate 55 the connection of a hose 86 thereto, while the upper end of said line may be similarly equipped to permit of the connection of another hose (not shown) thereto. In this way, it will be seen that 60 a stream of water may be discharged and selectively directed from the compartment 4 by occupants thereof.

In operation of the improved apparatus, with proper relative positioning of the mobile carrier 1, the elevating mechanism 3 may be distended or 65 elevated to any desired position by driving of the shaft 25, which in turn, will effect collective rotation of the screw-threaded shafts 31 engaging the collars 35 and hence, moving the pivotally connected ends of the levers 37 toward each 70 other. During raising of the elevating apparatus, bracing or supporting means will be afforded the compartment 4, in the form of the endless treads 55 engaged about the wheels 54, these treads engaging with a supporting surface 61 in

the fashion as is shown in the Figure 7 and thus, stabilizing the construction as it is raised. Also, and as hereinbefore described, the flooring of the compartment 4 will be maintained substantially level so as to afford safety to the occupants thereof through the compensating means connected between said wheels 54 and the compartment 4. Should it become necessary to effect inclining of the elevating mechanism longitudinally of the carrier 1 during either a raising or lowering of the same, this may be effected by transmitting pivotal movement in the desired direction to the pivotally mounted supporting arms 16 through the medium of the vertically disposed screw-threaded shafts 10 mounted in the annular frames 8 and adapted to be collectively rotated through the gearing mechanism hereinbefore described. Tilting or inclining of the elevating mechanism during either a raising or lowering operation of the same, transversely of the mobile carrier 1 may be selectively effected by rotation of the shaft 81 connected to the toggle mechanism 76, also hereinbefore specifically described. Consequently, upon the ability of the apparatus to be tilted either longitudinally or transversely, it will be understood that the compartment 4 may be directed to or returned from any desired objective with absolute accuracy.

Manifestly, the construction shown is capable of considerable modification and such modification as is within the scope of my claims, I consider within the spirit of my invention.

I claim:

1. In an apparatus of the character described, a bed, supporting arms pivotally mounted on the bed, a pair of annular frames fixedly mounted on the bed, vertically disposed screw-threaded shafts carried by each of said frames, said shafts having screw-threaded connection with the free ends of the supporting arms whereby to transmit collective pivotal movement thereto, a secondary bed carried upon the pivotal supporting arms, elevating mechanism pivotally mounted on said secondary bed movable in a direction at substantially right angles to said supporting arms, spring actuated means on said secondary bed connected to one side of the elevating mechanism for normally imparting an upward thrust thereto, means on the secondary bed connected to the opposite side of said elevating mechanism operable for effecting pivotal movement of the elevating mechanism against the normal thrust of said spring actuated means, and a compartment carried on the elevating mechanism.

2. In an apparatus of the character described, a bed, supporting arms pivoted at certain of their ends upon said bed, vertically disposed screw-threaded shafts mounted on the bed and having screw-threaded connection with the free ends of said supporting arms, means for effecting collective rotation of said screw-threaded shafts, a secondary bed pivotally supported upon said supporting arms and movable in a direction at substantially right angles to the path of pivotal movement of the supporting arms, an elevating mechanism upon the secondary bed, said elevating mechanism comprising a lazy-tong assembly, means on the secondary bed connected to the lowermost ends of the levers of said lazy-tong assembly for transmitting motion thereto whereby to optionally distend or collapse the same, spring actuated means on the secondary bed connected to one side of the elevating mechanism for normally imparting an upward and tilting thrust

thereto, other means mounted on said secondary bed and connected to the opposite side of said elevating mechanism operable for tilting said elevating mechanism in an opposite direction and against the thrust normally imparted thereto by said spring actuated means, a compartment carried upon the upper end of said elevating mecha-

nism connected to the free ends of the uppermost levers of the lazy-tong assembly thereof and means for effecting pivotal adjustment of said compartment with respect to said elevating mechanism.

HENRY FRANK BUCHHEIT.
